UNITED STATES PATENT OFFICE.

JOSEPH BOIVIN, OF PATERSON, NEW JERSEY, ASSIGNOR TO NEW IDEA METAL GOODS COMPANY, A CORPORATION OF NEW YORK.

COLLAR AND SHIRT SECURING DEVICE OR FASTENER.

Specification of Letters Patent. Patented Dec. 17, 1912

1,047,733.

Application filed November 10, 1909, Serial No. 527,222. Renewed April 1, 1911. Serial No. 618,382.

To all whom it may concern:

Be it known that I, JOSEPH BOIVIN, a citizen of the United States, residing at Paterson, in the county of Passaic and State of New Jersey, have invented certain new and useful Improvements in Collar and Shirt Securing Devices or Fasteners, of which the following is a specification, reference being had therein to the accompanying drawing.

10 My invention relates to improvements in devices for holding collars, shirts and neckties in position and partakes of the combined characters of a collar button and necktie holder.

15 The objects of my improvement are, first, to provide a comparatively flat and compact means for securing collar band to a shirt band and for holding the necktie; second, to provide a fastener or device for securing 20 collar and shirt together that will be light in weight, durable, compact, and noncorrosive; and third, to produce such a device in a simple and inexpensive form by bending a strip or plate of metal three times to form 25 four members substantially parallel to each other, and by providing some of said members with an embossed segment of a sphere, as illustrated in the accompanying drawing, in which:

30 Figure —1—, is an enlarged perspective view of my collar, shirt and tie fastener or securing device; Fig. —2—, a perspective view of a collar with a fastener or securing device inserted into the button hole (f); and 35 Fig. —3—, a perspective view of a collar showing a section of the outer portion of the collar broken away and this exhibiting a rear view of the fastener or securing device in position in button hole (f).

40 My collar, shirt and necktie holder consists of four members (a), (b), (c), and (d) formed by bending a strip or plate of metal three times. The member (a) is provided with an embossed segment of a sphere (e) 45 projecting outwardly from its face.

The collar band of a shirt is now ordinarily formed double with a button hole, in the lower rear turned down portion of the collar band, through which button hole a collar button is passed and adapted to secure the collar band of the shirt to the collar, by passing the collar button through the button hole (f) in either a stand up or a turned down collar. The shortest collar

buttons in use project so through the band 55 of the shirt and the inside band of the collar as to be objectionable and to interfere with the arrangement of a tie, and my invention being a flat and compact device is intended to obviate the objections and disadvantages of the projecting collar button.

50 My improved fastener is a W-shaped device and when in position the member (a) provided with an outwardly extending embossed segment of a sphere (e), projects upwardly inside of the turned down portion of the shirt collar band, said band resting in the loop formed by members (a) and (b). The members (c) and (d) are passed through the button hole (f) in the collar 70 and form a loop in which the necktie (g) is held in position between members (c) and (d). The band of the collar is held in position in the loop formed by the members (b) and (c), the shirt collar band is held in 75 the loop formed by the members (a) and (b) and the tie is held in the loop formed by the members (c) and (d) forming a fastener which securely locks collar, shirt and tie together in proper position.

80 It is obvious, referring to Fig. —2— of the drawings, how the shirt band rests in the loop formed by the members (a) and (b) and referring to Fig. —3— how the band of the collar is held in the loop formed 85 by the members (b) and (c) and how the necktie (g) is held in position in the loop formed by the members (c) and (d).

85 My invention may be composed of any suitable metal, but I prefer to manufacture it from aluminum which is not apt to be affected by perspiration or dampness and therefore will not corrode.

90 The device will be so made that there will be no sharp edges so that a necktie may be drawn in either direction to enable the wearer to tie it rapidly with facility.

95 The W-shaped device may be made to take up much less room than the ordinary collar button now in vogue.

100 It is obvious that my invention if made of aluminum may be light, durable, inexpensive and may be made in so compact a manner as to take up very little space.

105 With this description of my invention, what I claim as new, and desire to secure by Letters-Patent is:

A collar, shirt and necktie fastener, or

securing device, consisting of four members formed by bending a strip or plate of metal three times, to form a substantially W-shaped device, one of its members being provided with an embossed segment of a sphere projecting outwardly from the face of the member, substantially as set forth.

In testimony whereof I affix my signature in presence of two witnesses.

JOSEPH BOIVIN.
